PROCESS OF SETTING HIDES

Joseph D. Quick and George F. Mack,
Binghamton, N. Y.No Drawing. Application December 8, 1928,
Serial No. 324,797

10 Claims. (Cl. 149—5)

Our invention relates to the process of setting hides principally by means of a composition of matter placed upon the hides while in a stretched or extended condition, and it has for its object to cheapen the expense of mechanical appliance commonly used and to render the process more expeditious and simplified. In the production of hides for manufacture it is necessary after being dehaired etc. to stretch the same by expansion over frames or boards or table surfaces and there to fasten the stretched product in that situation and to hold the same by tacking or by other mechanical fasteners. Instead of depending solely upon nails or hand or mechanical fasteners and the time and expense incident thereto, we employ first, a suitable paste which is applied to the lower side of the hide or to the supporting surface for holding the hide in a stretched condition, and then apply to the upper hide surface a coating of our composition of matter which will hold the hide in a stretched condition and at the same time immediately permit the hide while held in its stretched condition to be removed from the stretching table or board surface and hung over a rail or bar for the removal of our surface composition, which may be said in a general way automatically removes itself. In the process of our invention above mentioned, we provide a surface application to the hide of ingredients or a composition made up as follows:—

One part of plaster of Paris
One part of starch
One part of borax
One part of water.

It is evident that this composition of matter is only temporarily adherent to the surface of the leather, but that when dried it will readily crumble and can be completely removed, the crumbling frequently occurring of itself.

The function of our composition as applied to the stretched hide is to maintain the hide in a stretched position when the composition solidifies or dries from exposure to the atmosphere.

Novel features of our invention are the preparation of a composition of matter comprised of materials commingled by our process and the application thereof to a hide under the conditions herein specified, said composition being adapted to hold the hide in set out condition while being dried, and to be easily and completely removed therefrom when dried. The hide is first stretched upon a setting table in a removable stretched position and the application of our composition may be upon the upper side, which may be either the flesh or the grain side of the hide

when in this position. The composition of matter is commonly commingled by mixing certain quantities of borax and starch together with water and thereafter by mixing with the same plaster of Paris and applying the composition to the hide while stretched upon an appropriate surface for treatment. Of course it is obvious that the composition may be applied to the underside of the hide before application to the table and then the upper side coated.

In the operation of our device we apply to the surface of the setting table a coating of liquid paste, and after the same has been thoroughly applied the hide is placed thereupon and stretched by hand and to its fullest extent and then fastened in its stretched condition in the manner provided and removably secured to the table surface. Those skilled in the art will recognize this as one way of performing the well known "setting out" process of securing hides to a setting table for further treatment, and that this process may or may not be applied to hides in a moist condition. We then apply to the outward surface of the hide in any manner the composition heretofore referred to by means of a brush or swab or any other convenient device. After the complete application of the composition is made we then immediately remove and lift the hide from the table surface and hang it over a rod or convenient stick or hood or other convenient supporting hanging device, and there it becomes thoroughly dried, and we then remove the composition in any convenient manner and thereafter wash the surface of the hide either mechanically, by hand, or machine, in any convenient manner until the surface is thoroughly cleaned of our composition.

While the proportions specified above have been found satisfactory, yet it is within the scope of my invention to vary such proportions without departing from the spirit of my invention.

We claim:—

1. The process of setting hides in the manufacture of leather comprising removably stretching hide upon a setting table and maintaining the hide so stretched thereon, applying to the upper surface of the hide a temporarily adhesive solidifying composition which will maintain the hide in stretched condition, and then removing the hide from the table.

2. The process of stretching hides comprising setting out a hide upon a setting table, and applying to the upper surface of the hide sufficient temporarily adhesive stiffening composition which will maintain the hide in stretched relation.

3. The process of setting a hide comprising stretching the hide on a surface, pasting the same to the surface, applying to the outer surface of the stretched hide a coating comprising 5 plaster of Paris, borax, starch and water, removing the hide while covered with the coating, hanging it over a support, leaving it there until the coating sets, and removing the same.

4. The art of setting a hide which consists 10 in stretching the same, fastening the same to a surface, applying a coating of commingled plaster of Paris, borax, starch, and water in liquefied form to the outer surface of the hide, lifting the hide from the surface and hanging 15 it over a hanger with the exterior surface covered with the coating until the coating sets.

5. The process of treating hides in the manufacture of leather which comprises setting out 20 a hide upon a setting table, applying a temporarily adhesive stiffening coating composition to the surface of the hide, removing the hide from the table, drying it and removing the coating therefrom.

6. The steps in the process of manufacturing 25 leather which consist in maintaining a hide in setting out condition by means of a coating of a temporarily adhesive composition of matter and entirely removing said coating.

7. A temporarily adhesive composition of matter 30 for use in drying hides, comprising plaster of Paris, starch, borax, and water, which becomes brittle upon drying and is completely and eas-

ily removable from the hide to which it has been applied, after the hide has dried.

8. A temporarily adhesive composition of matter for use in drying hides, comprising one part of plaster of Paris, one part of starch, one part of borax, and one part of water, which becomes brittle upon drying and is completely and easily removable from the hide to which it has been applied, after the hide has dried.

9. The process of treating leather which comprises removably attaching the leather to a smooth, rigid and rigidly supported surface, by means of liquid paste, setting out the leather upon said surface, coating the upper surface of the leather with a temporarily adhesive composition of matter which is adapted to maintain it in its stretched out condition, removing the so-coated leather from the rigid surface, drying it, and removing the coating of the composition of matter from its surface, whereby the leather is obtained in a flat condition and of substantially the same area as it had when removed from the rigid surface.

10. A composition of matter comprising plaster of Paris, a carbohydrate, and a mineral compound 10 having a slight alkaline reaction, the composition being adapted to maintain a hide in its stretched out condition after it has been set out upon a setting board.
